OVERSHOE WITH HEEL GRIP

Peter J. Hines, Montreal, Quebec, Canada, assignor to United States Rubber Company, New York, N. Y., a corporation of New Jersey

Application May 3, 1955, Serial No. 505,728

1 Claim. (Cl. 36—58.6)

This invention relates to an overshoe having an improved heel grip adapted to resist forces, such as the holding forces of mud and the like, which act to pull the overshoe off the shoe worn underneath when a person walks.

Heretofore, metal heel grips have been attached to the back of the overshoe upper. They were made of spring metal and were provided with inwardly extending lips which engage the top extended edge of the heel of the shoe over which the overshoe was worn. The engagement of the lip against the top extended edge of the heel of the shoe was designed to retain the overshoe on the shoe.

Such prior heel grips were objectionable because they were difficult to release from the heel of the shoe to permit the intentional removal of the overshoe, and they scratched the shoe over which they were worn. Furthermore, such heel grips being attached to the uppers after the overshoes were built, they presented an unattractive appearance, and sometimes they were uncomfortable to the foot of the wearer.

In accordance with the present invention, the heel grip is built into the back of the upper as an integral part of the overshoe while the latter is being constructed. The heel grip is made of soft, elastic, deformable rubber and it preferably engages the top extended edge of the shoe heel, but in the event the heel grip fails to engage such edge, its engagement with other portions of the shoe creates effective binding forces between the shoe and the overshoe to retain the overshoe in place. The heel grip made of such rubber has the further advantage of not scratching the shoe underneath. The rubber of the heel grip is sufficiently firm to provide a firm abutment to resist the passage of the heel grip over the extended top edge of the heel of the shoe after it has been seated against such edge. Since the heel grip is built into the overshoe upper, it does not alter the usual appearance of the overshoe, and the grip is also comfortable due to its resilient soft elastic character.

The improved overshoe containing the heel grip, the foregoing objects and advantages, and the method of making the overshoe are further described in the accompanying drawings, in which:

Fig. 1 is a side elevation of an overshoe embodying this invention, in which the heel, or quarter part of the upper, is broken away to show the cooperation of the improved heel grip with the heel of the shoe on the inside of the overshoe;

Fig. 2 is an enlarged vertical cross section of the overshoe shown in Fig. 1 and taken on line 2—2 thereof with the shoe removed;

Fig. 3 is a further enlarged vertical longitudinal cross section of the heel portion of the overshoe taken on line 3—3 of Fig. 2, but shown on a building last; and

Fig. 4 is a cross section of a modified form of a heel grip showing portions of the overshoe corresponding to similar portions in Fig. 3.

The invention is described in reference to a storm over-

2

shoe 10 shown in the several figures of the drawings, but it will be understood that the invention is applicable to the lower shell type of overshoe and high overshoes as well. The overshoe may be made of rubber, or rubber compositions or rubber like materials, which may be combined with fabric in accordance with the usual practice, and wherever rubber is used herein it shall include rubber compositions and rubber like materials.

The overshoe 10 is made in accordance with conventional practice, excepting for the construction of the heel grip 11, which is built into the back 12 of the overshoe upper 13, as an integral part thereof. As shown in Fig. 1, the heel grip 11 engages the top extended edge 14 of the shoe heel 15, which is attached to the upper 16 of the shoe 17, over which the overshoe 10 is worn.

The details of the heel grip 11, and the method of building it into the overshoe 10 are illustrated in Figs. 2 and 3. The heel grip 11 is made of a ridge of rubber 18 having a wedge shaped transverse cross section. The apex 19 of the ridge 18 projects inwardly from the back 12 of the overshoe upper. The apex 19 is preferably located at a height above the heel seat 20 to cause it to extend into the groove of the shoe 17 between the extended top edge 14 of the heel 15 and the upper 16 of the shoe 17, so as to retain the overshoe 10 on the shoe. However, it is not necessary for the apex 19 to extend into the groove, because the extending grip 11 creates effective pressure on other portions of the shoe to retain the overshoe in place in the event the apex fails to engage such groove. The heel grip 11 is located at the center of the back 12 of the upper, and it is preferably bisected by the longitudinal center line 21 of the overshoe, and it is located substantially in a plane, which extends parallel to the plane of the heel seat 20. The base 22 of the heel grip 11 is provided with a flange 23 on each side thereof, which is bonded to the back 12 of the overshoe upper.

A strip of reinforcing fabric 24 reinforces the base 22 of the heel grip 11 and the margin of a slot 25 in the fabric lining 26 of the overshoe through which the apex 19 of the heel grip 11 projects. The quarter 12 of the upper of the overshoe may consist of one or more layers 27 and 28 of rubber which back up the base 22 of the heel grip.

Excepting for the construction of the heel grip 11, the overshoe 10 is built up on a last 29 (Fig. 3) in accordance with the usual practice. For the purpose of building the heel grip 11 into the overshoe 10, the last 29 is provided with a groove 30 which extends in a plane substantially parallel to the plane of the heel seat surface 31 of the last. The insole 32 and the fabric lining 26 of the overshoe are assembled on the last 29 in accordance with the usual practice. The slot 25 is then cut in the lining 26 along a line extending opposite to the bottom of the groove 30 for a distance to each side of the center line 21 of the overshoe required to receive the projecting portion of the heel grip 11. The apex 19 of the unvulcanized ridge 18 of vulcanizable rubber is then inserted through the slot 25 until the flange 23 on its base 22 is pressed up against the back side of the fabric lining 26 in the area around the margin of the slot 25. The strip of reinforcing fabric 24 is then placed over the base 22 of the unvulcanized ridge of rubber 18. The strip of fabric 24 extends longitudinally of the slot 25, and is of sufficient width to extend over the margin of the slot so as to reinforce the area around the slot and the base 22 of the heel grip 11. The conventional layers 27, 28 of vulcanizable rubber are then applied, and the outsole and heel 33 is affixed in the conventional manner. All such overshoe parts are adhered together by the natural tack of the rubber, or with cement in accordance with the usual practice. The overshoe is then vulcanized

in accordance with conventional methods. After vulcanization, the heel grip 11 preferably has a Shore A durometer hardness of about 70 to 80.

A modified form of the heel grip 11' is shown in Fig. 4. The back 12' is provided with parts similar to the parts shown in Figs. 1 to 3, comprising a fabric lining 26', layers of rubber 27' and 28'. The inner layer of rubber 27' is positioned adjacent to the base 22' of the heel grip 11', and a frictioned strip of fabric 24' is interposed between the layers 27' and 28'.

While two forms of the invention have been shown and described herein in detail, it will be understood that changes may be made therein without departing from the spirit of the invention and it is intended to cover such changes as fall within the scope of the claim.

Having thus described my invention, what I claim and desire to protect by Letters Patent is:

An overshoe having a heel grip built therein comprising a ridge of rubber projecting inwardly from the back only of the quarter portion of the upper of greatest

curvature, the back of said upper comprising a fabric lining, a slot in said lining above and extending substantially parallel to the heel seat surface of said overshoe to each side of the center of the back of said upper, said ridge of rubber having a coextensive sharp apex projecting through said slot and presenting an exposed rubber surface, said ridge having a base and a flange of rubber on each side thereof extending along said slot and in rear of the margin thereof, said base and flanges being bonded to a layer of rubber in rear thereof and reinforced by a strip of fabric laid in behind said base and flanges.
